UNITED STATES PATENT OFFICE

WILLIAM F. KIESEL, JR., OF HOLLIDAYSBURG, PENNSYLVANIA

HOPPER CAR

Application filed September 25, 1930. Serial No. 484,256.

This invention relates to hopper cars and more particularly to the side and end construction of such cars and the manner in which the car body and slope floors at the ends thereof are supported upon the under-frame.

One object of the invention is to provide a transverse body bolster inclined from the vertical to bring the force acting on the bolster more nearly to the center line thereof when the car is under impact and the bolster must resist combined vertical and impact load.

Another object of the invention is to provide a bolster casting and side stake in an integral piece so as to obtain a strong connection between these members whereby outward bending forces on the side stakes are better resisted.

Another object of the invention is to provide improved means for supporting the slope floor of a hopper car, said means comprising an inclined body bolster in conjunction with a longitudinal triangular casting supported on the car center sill and filling the interspace between said slope floor, body bolster and center sill.

Another object of the invention is to provide an improved form of side truss terminating in jacking castings at the slope floors of the car body in lieu of the usual side sills common to hopper cars.

Still other important objects and advantages characterizing the invention will be evident from the detailed description, which follows hereinafter, of one embodiment or example of the invention, having reference to the accompanying drawings, whereof:

Fig. I represents a side elevation of one end of a hopper car with a portion broken away at the end of the body bolster.

Fig. II represents a longitudinal cross-section of the same, taken along the center line of the car.

Fig. III represents a transverse section of the same, taken as indicated by the lines III-III of Fig. I, and showing the transverse body bolster in detail.

Fig. IV represents an enlarged perspec-

tive view of a triangular casting disposed beneath the slope floor.

Fig. V represents a perspective view of the jacking casting; and,

Fig. VI represents a cross-sectional view of the bottom chord of a side truss taken as indicated by the lines VI-VI of Fig. I.

With particular reference to Fig. I, it will be seen that the hopper car is similar in general outline to cars now in use. Only one end of the car is shown, the other end being substantially identical. The side walls 1 are supported at intervals of their length by stakes 2 and are preferably formed with their upper portions 3 inclined inwardly and upwardly toward the center of the car. The stakes 2 are provided with extensions 4 on the outside of the side walls, which extensions terminate at the top rails 5. The top rails are shown in the form of Z-bars with their down-turned flanges 6 riveted to the side walls 1. At their bottom edges the side walls 1 are turned inward at 7, as shown in Fig. III, and are riveted to side truss bottom chords 8 in the form of relatively thick plates disposed at an angle of approximately 45° with the side walls 1.

The hoppers comprise side sheets 9, with their upper portions inclined outward and upward and riveted to the bottom chords 8 and abutting the lower edges of the side walls 1, slope sheets 10 riveted to the side sheets 9, and hinged doors 11 fitted with conventional locking devices 12. The slope sheets 10 of the end hoppers form a continuation of the slope floors 13 which extend from the end walls 14 down to the center sill 15. At the ends of the car the side walls 1 converge slightly at 16 toward the corner posts 17.

The corner construction of the car is similar to that described in detail in my pending application Serial No. 484,257, filed September 25, 1930. At the top rail 5, top corner castings 18 are provided, with their upper flat faces in some instances accommodating a grab iron 19 which forms the top rung of a side ladder 20. The top corner castings 18 are anchored to the upper ends of corner posts 17. At the lower end of each corner post there is a bottom corner

casting 21 which is formed at 22 to serve as a push-pole pocket. The bottom corner castings 21 are secured to the ends of end sills 23 and are braced in a horizontal plane 5 from the center sill 15 by means of diagonal braces 24, there being no extension from the side trusses of the hopper to the bottom corner castings 21. On one side of the car the bottom corner casting forms the lower term 10 minus of the side ladder 20. A suitable form of side step 25 may also be conveniently suspended from each bottom corner casting.

Immediately above the center plate 26, 15 which forms the point of support for a car truck, a transverse body bolster 27, shown in some detail in Fig. III, is provided. The body bolster is preferably made up of two separate wing castings joined together be- 20 neath the center sill 15 by the center plate 26 and above the center sill 15 by a plate 44. Each bolster 27 is securely riveted to the center sill and center plate at its lower flanges 29. The two bolster castings tied 25 together above and below the center sill form a truss with a diaphragm bounded by diagonal members 30, diverging toward the car sides, and intermediate members 31, forming stiffening webs whereby a rigid 30 structure is produced from end to end. An important feature of the invention is the inclination at which the body bolster is mounted on the center sill 15, the plane of the diaphragm of the bolster 27 being in- 35 clined from the bottom of the center sill so that it forms substantially a right angle with the slope floor 13, to which the flanges 32 are riveted. Accordingly, end and vertical forces are more fully counteracted by 40 the bolster than would be the case if the bolster were perpendicular to the center sill.

At the ends of the bolster 27, side stakes 45 are formed integrally with the respective wing castings of which the bolster is made, and the side stakes 28 are similarly inclined with respect to the center sill. By combining opposite stakes with the bolster castings there is provided a rigid connection more 50 capable of sustaining the outward bending force on the stakes. Where the slope floor 13 passes the upturned stake arms 28, the arms are flattened and widened, as designated at 42, and are secured, each to a side wall 1 and to an upturned flange 43 of the slope sheet 13.

Filling the triangular interspace between the center sill 15, bolster 27 and slope floor 13, there are a pair of parallel castings 33, 55 shown in perspective in Fig. IV. The castings 33 are centrally hollowed and provided with flanges 34 following the contour of the slope floor. The flanges 34 of the triangular castings, as well as flanges 32 of the body bolster are riveted to the slope floor

13, and they effect a tight seal preventing, for example, water impregnated with sulphur from passing through the floor. Oppositely turned flanges 35 on the triangular castings 33 are riveted to the center sill 15. 70

It will be apparent from the drawings that in lieu of the usual side sills extending to the bottom corners of the car, side trusses with bottom chords 8 terminating at the slope floors 13 have been utilized. At the 75 junctures of the slope floors and bottom chords 8, special castings or brackets 36, preferably made of cast metal, are provided, the same being shown in perspective in Fig. V. Each casting 36 is of angular construction and is formed at 37 with a foot or jacking pad. On the inside of the casting 36 there is an inclined face 38 which accommodates the end of a plate 8. By utilizing a bottom chord 8 in the form of a plate, no 80 forging or deformation is required at the jacking casting 36. Furthermore, the angle at which the plates 8 are inclined to the side walls 1 gives each plate as much transverse modulus as angles or other forms heretofore used as bottom chords for the car body. The angular extensions 39 of the jacking castings 36 are riveted at flanges 41 to the side walls 1. Furthermore, it will be noted that the bottom flanges 40 of the extensions 95 39 of the jacking castings 36 abut against the ends of the transverse body bolsters and are riveted to the ends of the bolster flanges 32. The vertical flanges 41 of the jacking castings are riveted to flanges 42 of stake arms 28. Accordingly, the bottom chords 8 are in effect supported upon the body bolsters and the necessity of carrying the bottom chords 8 beyond the slope sheets 13 to the end sills 23 is eliminated. By using a 100 plate for a bottom chord, inclined in the manner shown, in lieu of other forms of side sills, the car body construction can be kept cleaner both on the inside and outside, there being no cavities or projections for 105 the accumulation of coal, dirt, water or other matter likely to accelerate corrosion or deterioration of the parts of the car body. 110

In Fig. VI there is shown a cross-section of a bottom chord 8 at the center of a hopper, illustrating how the side walls 1 join the side sheets 9 of a hopper on the inside of the bottom chord. It will be noted the bottom edges of the side walls 1 abut against the top edges of side sheets 9 in such manner that there is no overlap or angular cavity for the accumulation of water, dirt or the like, and a smooth sloping surface is provided. 115

While I have described in some detail one 120 embodiment or example of my invention as applied to a hopper car, it will be apparent, especially to those skilled in the art, that various changes may be made in the form 125 of the car construction herein disclosed with- 130

out departing from the spirit of the invention as defined in the annexed claims, and that certain features of the invention may at times be used to advantage without a corresponding use of other features.

Having thus described my invention, I claim:

1. In a freight car end construction, a slope floor, and a transverse body bolster in a plane at substantially right angles to said slope floor.

2. In a freight car end construction, a slope floor, a transverse body bolster at substantially right angles to said slope floor, and side stakes formed integrally with said body bolster.

3. In a freight car end construction, a center sill, a slope floor forming an acute angle with said center sill, and a transverse body bolster tied to said center sill and inclined thereto to brace said slope floor at substantially right angles.

4. In a freight car end construction, a center sill, a slope floor forming an acute angle with said center sill, a transverse body bolster on said center sill and inclined toward the center of the car, and a triangular casting occupying the space bounded by said center sill, slope floor and body bolster.

5. In a freight car end construction, a center sill, a slope floor forming an acute angle with said center sill, a transverse body bolster on said center sill and inclined toward the center of the car, and a triangular casting occupying the space bounded by said center sill, slope floor and body bolster, said body bolster and triangular casting having supporting flanges for the slope floor following the contour thereof.

6. In a freight car end construction, a center sill, a slope floor inclined downward from the end of the car toward the center and a body bolster at substantially right angles to said slope floor, said body bolster comprising two castings tied together above and below said center sill.

7. In a freight car construction, an end slope floor, a longitudinal side truss including a bottom chord, and a bracket forming the terminus of said side bottom chord and having an angular extension paralleling said slope floor and secured to the edges thereof.

8. In a freight car construction, an end slope floor, a longitudinal side truss including a bottom chord, and a bracket forming the terminus of said side bottom chord, and having an angular extension paralleling said slope floor and secured to the edges thereof, said bracket being formed to serve as a jacking pad.

9. In a freight car construction, an end slope floor, a side truss including a flat plate inclined inwardly from the car sides, and a bracket forming the terminus of said flat plate, said bracket having an inclined seat

adapted to accommodate the said flat plate, and an angular extension paralleling the slope floor and secured to the edges thereof.

10. In a freight car construction, an end slope floor, a side truss including a flat plate inclined inwardly from the car sides, and a bracket forming the terminus of said flat plate, said bracket having an inclined seat adapted to accommodate the said flat plate, an angular extension paralleling the slope floor and secured to the edges thereof, and said bracket being formed to serve as a jacking pad.

11. In a freight car, end slope floors, body bolsters beneath said slope floors, and side trusses extending along the sides of the car between said body bolsters, said side trusses having bottom chords terminating in a bracket secured to the ends of said body bolsters.

12. In a freight car, end slope floors, body bolsters beneath said slope floors, and side trusses including bottom chords extending along the sides of the car between said body bolsters, said bottom chords terminating in a bracket secured to the ends of said body bolsters, and said bracket being formed to serve as a jacking pad.

13. In a hopper car, side walls turned inwardly at their lower edges toward the hoppers, hopper side sheets turned outwardly at their upper edges to substantially abut said side walls, and a flat plate secured to the turned edges of said side walls and hopper side sheets and forming the bottom chord of a side truss for the car body.

14. In a hopper car, end slope floors, side walls turned inwardly at their lower edges toward the hoppers, hopper side sheets turned outwardly at their upper edges to abut said side walls, and a flat plate secured to the turned edges of said side walls and hopper side sheets forming the bottom chord of a longitudinal truss extending from one slope floor to the other.

15. In a hopper car, end slope floors, side walls turned inwardly at their lower edges toward the hoppers, hopper side sheets turned outwardly at their upper edges to abut said side walls, and a flat plate secured to the turned edges of said side walls and hopper side sheets forming the bottom chord of a longitudinal truss extending from one slope floor to the other, said flat plate sloping inwardly and downwardly toward the hoppers.

16. In a freight car, a center sill, a car body supported thereon including hoppers and end slope floors leading thereto, transverse body bolsters near the ends of said center sill inclined towards each other and disposed beneath said slope floors, and side trusses for the car body confined between said bolsters and tied to the ends thereof.

17. In a freight car, a center sill, a car

body supported thereon including hoppers and end slope floors leading thereto, transverse body bolsters near the ends of said center sill and disposed beneath said center sills and side trusses for the car body confined between said bolsters, said side trusses comprising bottom chords terminating in angular brackets at said slope floors, and said angular brackets being tied to the ends of said bolsters.

10 18. In a freight car, a center sill, a car body supported thereon including hoppers, and end slope floors leading thereto, transverse body bolsters near the ends of said center sill inclined towards each other to form substantially right angles with said slope floors, and side trusses for the car body having their bottom chords confined between said bolsters, said bottom chords terminating in angular brackets tied to the ends of said bolsters.

15 19. In a freight car end construction, a center sill, a slope floor forming an acute angle with said center sill, and a body bolster having a diaphragm extending from the bottom of said center sill to said slope floor in a plane substantially at right angles to said slope floor.

20 20. In a freight car end construction, a center sill, a slope floor forming an acute angle with said center sill, and a body bolster having a diaphragm extending from the bottom of said center sill to said slope floor in a plane substantially at right angles to said slope floor, said body bolster comprising wing members tied together above and below said center sill and having side stakes formed integral therewith.

25 In testimony whereof, I have hereunto signed my name at Altoona, Pennsylvania, this 22nd day of September, 1930.

WILLIAM F. KIESEL, JR.
